UNITED STATES PATENT OFFICE.

GEORGE GODDU, OF WINCHESTER, MASSACHUSETTS, ASSIGNOR TO UNITED SHOE MACHINERY CORPORATION, OF PATERSON, NEW JERSEY, A CORPORATION OF NEW JERSEY.

WORK-SUPPORT.

1,384,830.

Specification of Letters Patent. Patented July 19, 1921.

Application filed August 1, 1918. Serial No. 247,738.

To all whom it may concern:

Be it known that I, GEORGE GODDU, a citizen of the United States, residing at Winchester, in the county of Middlesex and State of Massachusetts, have invented certain Improvements in Work-Supports, of which the following description, in connection with the accompanying drawings, is a specification, like reference characters on the drawings indicating like parts in the several figures.

This invention relates to work supports and to work support controlling means which are particularly adapted to machines for use in the manufacture of boots and shoes and is herein shown as embodied in a construction comprising a work support of the jack type such as is employed in connection with a machine for inserting fastenings. The machine in which the invention is shown incorporated is especially adapted for the insertion of fastenings on the heel seats of the soles of boots and shoes. It will be understood, however, that the invention is applicable to other types of machines and is capable of utilization in connection with other types of work supports.

It is desirable that the work in all cases be clamped firmly during the insertion of fastenings in order that the parts to be secured or nailed or studded will be held fixedly in proper position and the fastenings fully and properly inserted. Heretofore considerable difficulty has been encountered in securing proper clamping pressure on work as it is presented to the fastening inserting mechanism due in part to differences in depths and conditions of last pin holes of lasts on which the work is mounted, but more generally to differences in the thickness of the work, as for instance in the height of heels, to differences in the height of lasts, and to other differences tending to a lack of uniformity in characteristics of the work. Commonly in machines used for the insertion of fastenings as heretofore constructed, adjustment of the work support to provide for proper clamping of the work has been carried out by manually operated means. Because of variations in the work and in the conditions attendant upon presentation of work to the operating instrumentalities as described above, frequent adjustment of the work support became neces-

sary or, at least, desirable. As a matter of practice, however, the support was adjusted only for marked variations in the thickness of the work or in the heights of the lasts on which the work was mounted. This was due to the inconvenience and general un-desirability of the manual adjustment of the work support which demanded of the operative the exercise of considerable skill and judgment since no work measuring means was provided.

It is an object of the present invention to provide improved means for measuring the work and for insuring the application of proper clamping pressure thereon for all variations in thickness or other characteristics of the work as presented to the machine.

Features of the invention consist in a novel organization of means for rendering the work support automatically adjustable to variations in the work wherein the construction and arrangement preferably are such that the work is measured and has final clamping pressure applied thereto before the machine is started.

My invention contemplates also a novel form of work support in which the means for applying final work-clamping pressure is manually operated and controls means for measuring the work preliminary to the application of such pressure.

Other important features and objects of the invention will appear from the following description and claims when considered in connection with the accompanying drawings.

In the drawings, Figure 1 is a side elevation view partly in section showing my invention applied to a fastening inserting machine;

Fig. 2 is a detailed front view of a portion of the work measuring mechanism of my invention;

Fig. 3 is a detailed side view of portions shown in Fig. 2, and

Fig. 4 is an extensible connection between the starting treadle and the cam which controls the measuring mechanism.

For the purpose of illustration, the invention is shown embodied in a fastening inserting machine of the type disclosed in the Letters Patent No. 1,030,775, granted June 25, 1912, to George Goddu, the said machine

consisting of fastening inserting mechanism indicated by reference character 4 having the usual work abutment 6 and work gage 8. Mounted in the frame 10 of the machine is 5 the usual horn or jack shaft 12 which rests at its lower end on lever 14, the connection between the jack shaft 12 and lever 14 comprising a slidably pivoted block 16, the construction of the lever and connection being 10 exactly as shown in the patent to Goddu No. 1,011,941, granted December 19, 1911, to which reference should be had for a detailed account of this part of the structure. Briefly, the mechanism for lifting the jack 15 shaft 12 consists of the lever 14 already mentioned to which there is pivoted at 18 the lower link 20 of a toggle comprising an upper link 22 pivoted to the lower end of a slide 24 which is reciprocable in a casing 26 fix- 20 edly secured to the machine frame. Slide 24 is locked to its casing or surrounding bracket by means disclosed in the last-mentioned patent whenever the toggle is broken to cause the work-releasing movement of the work 25 support while the work is being fed. Adjustably attached to the upper end of the slide 24 is a rod 28 surrounded by a heavy spring 30 extending from the collar 32 on the rod 28 to a partition plate located at 34 30 in the machine frame. To make and break the toggle there is pivoted at 36 on the machine frame a bell crank lever 38 connected by a link 40 with the pivot 42 of the toggle links 20 and 22, said bell crank 38 being operated in properly timed relation with respect to the inserting mechanism by means of a cam on the main shaft 44 through a link 46 attached to the upper arm of the bell crank. After the work has been placed upon the jack 40 spindle 48 the same may be elevated to press the work against the abutment 6 by depressing the treadle 50, the latter being connected by a link 52 to a bell crank 54 pivoted at 56 and having a cam portion 58 which cooperates with a cam projection 60 on one part of 45 a two-part lever 14 to raise the jack shaft 12 as said part of the lever 14 moves with respect to the other part about the pivot 62 as a fulcrum, it being understood that the machine comes to rest with the toggle 20, 22 in 50 the position shown in Fig. 1. The construction and arrangement of the jack spindle is such that the work mounted thereon is pressed against the abutment 6 when the machine is at rest. Initial upward movement 55 of the supporting member for the jack spindle is followed by locking of the spindle to its supporting member after which said part of the lever 14 ceases to turn about 62 as a fulcrum and turns instead about pivot 64 in the block 16 thus raising the free end of the other part of the lever and through the toggle mechanism and rod 28 compressing the spring 30 and in this manner effecting final 60 clamping pressure on the work. Following

this, further or continued downward movement of the treadle 50 causes the actuation of the shaft 44, and hence of the power means for operating the work support and the inserting mechanism, through the upward movement given to the rod 66 which controls the clutch starting mechanism on shaft 44, there being a yoke connection 68 between the rear end of the treadle 50 and the said rod 66. All of the mechanism thus 70 far described will be found set forth in detail in the patent to Goddu No. 1,011,941, referred to above. A separate treadle 69 may be provided for starting the machine, this arrangement being such that the work 80 support remains in lowered or work-receiving position while the fastening inserting mechanism is operated.

Mounted upon the horn or jack shaft 12 is the work support mechanism shown in the present embodiment of the invention to comprise a jack spindle 48 pivoted on a transverse axis 70 to a plate 72 mounted to rock on an axis at right angles to the first-mentioned axis, in a manner similar to that shown in the patent to Cuff, No. 919,424, granted April 27, 1909, and carried by a slide 74 having conveniently shoulders or projections 76 to which are attached the corresponding ends of two springs 78 preferably of the form shown in Fig. 1 of the drawings, the other ends of said springs being attached by screws 80 to a housing 82 fixedly secured to the lower end of a bracket 84 in which housing the plate 74 is slidably received. The housing 82 and bracket 84 constitute a supporting member for the plate 74 and the parts carried thereby. The plate or slide 74 is retained in its housing by means of a pin-and-slot connection indicated at 83. Upon reference to Fig. 2 of the drawings it will be observed that the plate 74 is provided with rack teeth 86 at its opposite edges, the rack teeth on one edge facing upwardly and those on the other edge downwardly.

Mounted in the housing 82 are pawls 88 and 90 pressed upon by plungers 92 and 94, respectively, the latter being backed by springs 96, the construction and arrangement being such that the pawls are pressed in a direction to engage the teeth 86 on plate or slide 74. The said pawls, however, are normally kept out of contact with the teeth of the slide by means of a cam plate 98 connected by an extensible connecting member 100 with the treadle 50. Extending from a fixed member 102 on the frame 10 is a curved arm 104 carrying at its free end a screw threaded adjustable member 106 arranged to be interposed in the path of movement of the flange 108 at the upper end of plate 98. The extensible connection referred to above comprises a rod 110 connected at its lower end to the treadle 50 130

and slidably engaged in guideways 112, 114, in the member 116, the said rod 110 carrying a collar 118 between which and the guide 112 is interposed a spring 120 surrounding the rod 110. The upper end of member 116 is pivotally connected at 122 to the lower end of the cam plate 98.

When the machine is at rest the last on its supporting jack spindle 48 is normally 10 pressed into contact with the abutment 6 by means of the springs 78 since the pawls 88 and 90 are held out of contact with the plate 74 by means of the cam plate 98. In order to remove the work the operative pulls 15 the jack spindle 48 forwardly from beneath the abutment 6, the said spindle rising the full height permitted by the pin and slot connection 83 under the tension of springs 78. The work is then removed and work 20 on another last substituted and located under the abutment 6 by shoving the jack spindle rearwardly and downwardly against the action of the light springs 78. When the work is in position the operative 25 presses treadle 50 to move the cam plate 98 downwardly and simultaneously lift the housing 82 on the supporting member 84 through connections with the lever 14, the result being that the cam plate 98 and the 30 locking pawls 88 and 90 are both moved in directions away from each other so that finally the pawls engage the teeth 86 on the slide 74 and lock the said slide to the housing on the supporting member 84. During 35 the time that the plate or slide 74 moves relatively to the housing 82 of member 84, the work is supported in contact with the abutment through the action of springs 78 only, and the work support mechanism 40 adjusts itself automatically to the thickness of the work. As soon as the locking pawls engage the teeth on the plate 74, pressure is applied to the work through the lever 14 as it turns about the fulcrum point 64 in 45 applying gradually increasing pressure on the spring 30. Before the treadle is fully depressed bell crank 54 has completed its operation on lever 14 and the work is under final clamping pressure supplied by the 50 strong spring 30. On the completion of the downward movement of the treadle the clutch on the main shaft is actuated to start the fastening inserting mechanism in operation. Thus the work is held firmly for 55 the impact of the fastening inserting mechanism. As the machine continues to operate the work support is lowered through the breaking of the toggle 20, 22, to permit the work to be fed, the spring 30 being held 60 under compression through locking of the slide 24 in its housing 26 as disclosed in the patents to Goddu referred to above. At the end of the feeding movement the toggle is again straightened and the spring 30 rendered operative to press the work firmly 65

against the abutment while the fastening is being driven. The work support never descends far enough during the work feeding operations to unlock the spindle from its supporting member. Adjustment of the 70 member 106 in its supporting arm 104 will determine the amount of movement of the plate 98 directly by the treadle. If, for instance, the adjustable member 106 is adjusted downwardly greater movement of the 75 plate 98 by the treadle will be permitted and hence the locking pawls will engage the slide 74 earlier in the cycle of operations, thus holding the fulcrum point 64 at a lower point with the result that greater pressure 80 is placed upon the work through the increased pressure on spring 30 as the lever 14 is turned about said fulcrum point. On the other hand, if the adjustable member 106 is adjusted upwardly so that there is 85 little or no downward movement of the plate 98 when the treadle is depressed, then the supporting member 84 and its housing 82 must in their upward movement release the pawls 88 and 90 from the cam plate 98 90 to lock the jack spindle to its supporting member with the result that the fulcrum point 64 is moved upwardly to a greater extent than before and thus less pressure is placed upon the spring 30 as the lever 14 95 turns about said fulcrum point. Obviously, the locking pawls and, through said pawls, the work measuring means are both controlled by the treadle and by the mechanism for applying final clamping pressure 100 on the work.

It will be clear that the mechanism described above provides a means for insuring the application of uniform pressure upon the work even though the work varies considerably in thickness. This is due to the fact that the work is preliminarily pressed against the abutment 6 by the springs 78 and to the construction which permits relative movement between the support 48 and 105 the actuating member 14 until the locking pawls finally become operative to lock these parts together so that a firm clamping pressure on the work is supplied through lever 110 14 and the spring 30. 115

Having described my invention, what I claim as new and desire to secure by Letters Patent of the United States is:—

1. In a machine of the class described, a work support movable between work-receiving and work-clamping positions, means for measuring the work comprising a spring normally operative to lift the work support to work clamping position, and manually operable means for applying final work-clamping pressure constructed and arranged to control said measuring means. 120
2. In a machine of the class described, an abutment, a work support movable between work-receiving and work-clamping positions, 125
3. In a machine of the class described, 130

means for measuring the work comprising a spring normally operative to press the work on the support against the abutment, and means for applying final work-clamping pressure comprising manually operated means constructed and arranged to start the machine in operation subsequent to the measuring and work-clamping operations.

3. In a machine of the class described, a work support movable between work-receiving and work-clamping positions, means comprising a spring for measuring the work, means for locking the support against movement after measurement has been effected, manually operable means for applying final work-clamping pressure, and means separate from said manually operable means for controlling the locking means.

4. In a machine of the class described, a work support movable between work-receiving and work-clamping positions, means comprising a treadle for moving the work support toward work-clamping position, means operating yieldingly to press the work support in the same direction, means for locking the work support to said first-mentioned means, and controlling means for said locking means separate from the moving means and operable to cause the work support to be locked to the moving means at a determined point in the operation thereof.

5. In a machine of the class described, a work support movable between work-receiving and work-clamping positions, means for starting the machine, means comprising a spring for measuring the work, means for locking the support against movement in a direction to compress said spring after measurement has been effected, means actuated by said starting means for controlling the locking means, and means separate from the controlling means for applying final work-clamping pressure.

6. In a machine of the class described, a work support movable between work-receiving and work-clamping positions, a work abutment, means comprising a spring for normally pressing the work on the support yieldingly against said abutment, treadle-operated means for moving the support toward said abutment, and means controlled by said treadle-operated means for locking the work support against movement by said spring.

55. 7. In a machine of the class described, a work abutment, a work support movable between work receiving and work clamping positions, a supporting member therefor, treadle operated means for moving the supporting member to lift the work support toward said abutment, and means separate from said treadle operated means and controlled by said treadle for locking the work support to its supporting member.

8. In a machine of the class described, a work abutment, a work support movable between work-receiving and work-clamping positions, a supporting member therefor, means for yieldingly pressing the work on the support against said abutment, treadle-operated means for moving the supporting member to lift the work support toward said abutment, and means separate from the treadle operated means and controlled by said treadle for locking the work support in work-clamping position.

9. In a machine of the class described, a work abutment, a work support, a supporting member therefor, said work support being movable relatively to its supporting member between work-receiving and work-clamping positions, means for yieldingly pressing the work on the support against said abutment, means for locking the support against operation by said pressing means, and means distinct from said locking means and operable on said supporting member to apply final clamping pressure on the work before the machine is started in operation.

10. In a machine of the class described, a jack spindle movable between work-receiving and work-clamping positions, a supporting member therefor, spring means interposed between the spindle and its supporting member for moving the spindle toward work-clamping position, and manually controlled means for locking the spindle to its supporting member against movement by said spring.

11. In a machine of the class described, a work support movable between work-receiving and work-clamping positions, a supporting member yieldingly connected thereto, means for periodically depressing said supporting member, means for starting the machine, and means controlled by said starting means for causing relative movement between the work support and its supporting member.

12. In a machine of the class described, a work support movable between work-receiving and work-clamping positions, a supporting member therefor, means for periodically depressing said supporting member, means for starting the machine, and means controlled by said starting means for locking the work support to its supporting member, said locking means being constructed and arranged to retain the work support in locked relation to the supporting member upon depression of said member.

13. In a machine of the class described, a jack spindle movable between work-receiving and work-clamping positions, a supporting member therefor, means for starting the machine, means controlled by said starting means for moving the spindle toward work-

clamping position, and means carried by the supporting member for locking the spindle to the supporting member.

14. In a machine of the class described, a jack spindle movable between work-receiving and work-clamping positions, a supporting member therefor, manually operable means for moving the spindle toward work-clamping position, means for periodically depressing the supporting member, and means controlled by said first-mentioned means and operable upon the supporting member for yieldingly moving the spindle in the same direction as said first-mentioned means.

15. In a machine of the class described, a jack spindle movable between work-receiving and work-clamping positions, a supporting member therefor, means for moving the spindle toward work-clamping position, power means for moving the supporting member and spindle toward and from work-clamping position, and means controlled by said first-mentioned means for locking said spindle to its supporting member during a complete cycle of operation of the power means.

16. In a machine of the class described, a work support movable between work-receiving and work-clamping positions, a supporting member therefor, means for starting the machine, means for effecting relative movement of the spindle and its supporting member and for locking the spindle in proper relation to the supporting member, and means operable by said starting means and movable relatively to the supporting member for controlling the locking means.

17. In a machine of the class described, a work support movable between work-receiving and work-clamping positions, said support comprising a jack spindle and a supporting member therefor, means for controlling the movements of the spindle relatively to its supporting member, means for starting the machine, and a cam controlled by said starting means for controlling said first mentioned means.

18. In a machine of the class described, a work support movable between work-receiving and work-clamping positions, means for starting the machine, means actuated by the starting means and controlled by the thickness of the work for applying final work-clamping pressure prior to the starting of the machine, and means movable relatively to the pressure applying means for controlling the application of pressure to the work support.

19. In a machine of the class described, a work support movable between work-receiving and work-clamping positions, a supporting member therefor, connections be-

tween the work support and its supporting member controlled by the thickness of the work, means for starting the machine, means for applying final pressure to the work, and means operable by the starting means and movable relatively to the pressure applying means for controlling the application of pressure to the work support.

20. In a machine of the class described, a work support movable between work-receiving and work-clamping positions, and means for securing uniform pressure on work of various thicknesses at the time of fastening insertion comprising means for moving the support to final work clamping position before the machine is started, a work-controlled connection between said moving means and said support, and fixed means for determining the point at which the connection is made.

21. In a machine of the class described, a work abutment against which the work may be clamped, a work support movable between work-receiving and work-clamping positions, means for keeping the work on the support normally pressed against said abutment, power means for moving the work support toward and from said abutment, and means for locking the work support to said power means prior to the starting of the machine.

22. In a machine of the class described, a work abutment against which the work may be clamped, a work support movable between work-receiving and work-clamping positions, means operative while the machine is at rest for yieldingly pressing the work on the support against the abutment, and treadle-operated means for operating the work support to apply final pressure to the work.

23. In a machine of the class described, a work support movable between work-receiving and work-clamping positions, a supporting member therefor, means operative for pressing the work support toward work-clamping position, a treadle, means for locking said work support to its supporting member, and means actuated by said treadle and movable relatively to said pressing means for controlling the locking means.

24. In a machine of the class described, a jack spindle movable between work-receiving and work-clamping positions, a supporting member therefor, manually operable means for pressing the spindle and its supporting member toward work-clamping position, means for moving the spindle relatively to its supporting member, and cam-controlled means for locking the spindle to its supporting member as said support moves under the action of said pressing means.

25. In a machine of the class described, a

- 8
- work abutment, a work support movable between work-receiving and work-clamping positions, a supporting member therefor, means for pressing the work on the support 5 normally in contact with said abutment, means for locking the work support to its supporting member, a treadle-controlled cam for controlling said locking means, and means for moving the supporting member 10 relatively to the work support, the construction and arrangement being such that at a point, in the movement of the supporting member, determined by said cam the locking means becomes operative to lock 15 the work support to its supporting member.
26. In a machine of the class described, a work abutment, a work support movable between work-receiving and work-clamping positions, a spring operative to hold the 20 work on the support normally against the abutment while the machine is at rest, and manually operable means controlled by the work introduced between the support and abutment for applying final clamping pressure on the work.
27. In a machine of the class described, a work support movable between work-receiving and work-clamping positions, a spring for holding the work support normally in 30 work-clamping position, said work support being so mounted that it may be readily depressed directly by the workman in placing work thereon, and manually operated means for pressing the support toward work- 35 clamping position.
28. In a machine of the class described, a work support movable between work-receiving and work-clamping positions, a spring for holding the work support normally in 40 work-clamping position, and manually operated means for yieldingly applying final clamping pressure to the work on the support.
29. In a machine of the class described, a work support movable between work-receiving and work-clamping positions, means for holding the support normally in work- 45 clamping position, and yieldingly operated means for causing the application of maximum clamping pressure on the work prior to the operation of the machine.
30. In a machine of the class described, a jack spindle movable between work-receiving and work-clamping positions, means for 50 measuring the work, and manually operable means for applying final work-clamping pressure constructed and arranged adjustably to control said measuring means.
31. In a machine of the class described, a 55 jack spindle, a supporting member therefor, means for measuring the work on the support, power means for operating the support, and means for applying final work- 60 clamping pressure, comprising means for securing the support in fixed relation to its

supporting member during a plurality of operations of said power means, the construction and arrangement being such that the work is measured and has final clamping pressure applied thereto before the machine is started. 70

32. In a machine of the class described, work supporting mechanism comprising relatively movable parts, manually operable means for moving said mechanism, means 75 independent of said manually operable means for effecting relative movement of the parts of said mechanism to measure the work, and controlling means for said measuring means including a member station- 80 arily mounted on the machine frame.

33. In a machine of the class described, work supporting mechanism comprising relatively movable parts, manually operable means for effecting relative movement of 85 said parts to measure the work, manually operable means for moving said mechanism, and means mounted independently of said manually operable means for controlling the extent of relative movement of said parts. 90

34. In a machine of the class described, work supporting mechanism comprising relatively movable parts, manually operable means for effecting relative movement of said parts to measure the work, and means 95 intermediate between the parts of said mechanism for securing said parts against relative movement arranged to operate immediately following actuation of the means for effecting relative movement of 100 said parts.

35. In a machine of the class described, work supporting mechanism comprising relatively movable parts, manually operable means for effecting relative movement of 105 said parts to measure the work, means for operating said mechanism, manually operable means for applying final work clamping pressure on the work, and means independent of the operating means for securing said parts against relative movement during a plurality of cycles of operation of the machine. 110

36. In a machine of the class described, work supporting mechanism comprising relatively movable parts, manually operable means for effecting relative movement of said parts operable to lift the work holding part of the support to work clamping position, means for operating said mechanism, manually operable means for applying work clamping pressure to said mechanism and means for securing said parts against relative movement upon actuation of the operating means. 115

37. In a machine of the class described, work supporting mechanism comprising relatively movable parts, manually operable means for effecting relative movement of 120 said parts operable to lift the work holding 125

part of said mechanism to work clamping position, means for operating said mechanism comprising a member connected thereto, means for imparting to said member a movement different from its operating movement, and means for applying work clamping pressure to the work support upon such movement of said member.

38. In a machine of the class described, 10 work supporting mechanism, comprising relatively movable parts, means for operating said mechanism comprising a substantially horizontal member arranged to uphold the work supporting mechanism, means 15 for applying final work clamping pressure to said mechanism constructed to raise said member positively, and means for securing said parts together upon operation of said pressure applying means.

39. In a machine of the class described, a 20 work support, a supporting member therefor, said work support being movable relatively to its supporting member to measure the work on the support, manually operable 25 means for moving the supporting member, and means supported independently of said manually operable means for securing the work support to its supporting member upon operation of the manually operable 30 means.

40. In a machine of the class described, a work support movable between work receiving and work clamping positions, a supporting member therefor, means comprising 35 a spring for effecting movement of the support relative to the supporting member to measure the work, manually operable means for applying final work clamping pressure, and means independent of the manually operable 40 means for securing the support against movement relatively to its supporting member.

41. In a machine of the class described, a work support, a supporting member therefor, said work support being movable relatively to its supporting member to measure the work on the support, manually operable 45 means for moving the supporting member, means for securing the work support to its supporting member upon operation of the manually operable means, a slide for controlling the securing means, and means for adjustably positioning said slide.

42. In a machine of the class described, a 55 work support, a supporting member therefor, said work support being movable relatively to its supporting member to measure the work on the support, manually operable means for moving the supporting member, 60 means for securing the work support to its supporting member upon operation of the manually operable means, a member for controlling the securing means, and means for operating the controlling member upon actuation of the manually operable 65 means.

43. In a machine of the class described, a work support, a supporting member therefor, said work support being movable relatively to its supporting member to measure the work on the support, manually operable 70 means for moving the supporting member, means for securing the work support to its supporting member upon operation of the manually operable means, a member for controlling the securing means, a yielding connection between the controlling member and said manually operable means, and means for adjustably limiting the movement of said controlling member upon actuation of the manually operable means. 75

44. In a machine of the class described, a work support, a supporting member therefor, said work support being movable relatively to its supporting member to measure the work on the support, manually operable 80 means for moving the supporting member, pawl and ratchet connections between the work support and its supporting member for securing them together, and means operated by the manually operable means for controlling said connections. 85

45. In a machine of the class described, a work support, a supporting member therefor, said work support being movable relatively to its supporting member to measure 90 the work on the support, manually operable means for moving the supporting member, means for securing the work support to its supporting member at a predetermined point in the upward movement of the supporting 100 member, a member for controlling the securing means, and means for raising the controlling member when the supporting member is again lowered by the release of said pressure applying means thereby to 105 disconnect said work support from its supporting member at a point above its point of connection thereto. 105

46. In a machine of the class described, a work abutment, a work support, manually 110 operable means for applying final work clamping pressure on the support, and means independent of said manually operable means for pressing the work on the support against the abutment. 115

47. In a machine of the class described, a work support, a supporting member therefor, said work support being movable relatively to its supporting member to measure the work on the support, manually operable 120 means for moving the supporting member, means operable upon movement of the supporting member to lock the work support thereto and means independent of the supporting member for controlling the locking means. 125

48. In a machine of the class described, a work support, a supporting member therefor, said work support being movable relatively to its supporting member to measure the work on the support, means for securing 130

the work support to its supporting member, manually operable means comprising a spring for applying final clamping pressure to the work support, and means interposed 5 between the supporting member and said spring for automatically operating the work support.

49. In a machine of the class described, a work support, a supporting member therefor, said work support being movable relatively to its supporting member to measure the work on the support, manually operable means comprising a spring for applying final clamping pressure to the work support, 10 means interposed between the supporting member and said spring for automatically operating the work support and constructed 15 to compensate for variations in the thickness

of a piece of work, and means for securing the work support and its supporting member in locked relation during the operation of said work support operating means.

50. In a machine of the class described, work supporting mechanism comprising parts normally relatively movable, means 25 for effecting relative movement of said parts arranged to lift the work holding part of the support to work clamping position and thereafter to apply work clamping pressure to said mechanism, means for operating said mechanism, and a locking device for securing said parts against relative movement upon actuation of the operating means.

In testimony whereof I have signed my name to this specification.

GEORGE GODDU.
